US00D677666S

(12) **United States Design Patent**
Akana et al.

(10) **Patent No.:** **US D677,666 S**
(45) **Date of Patent:** ** *Mar. 12, 2013

(54) **BACKPLATE OF AN ELECTRONIC DEVICE**
(75) Inventors: **Jody Akana**, San Francisco, CA (US); **Bartley K. Andre**, Menlo Park, CA (US); **Jeremy Bataillou**, San Francisco, CA (US); **Daniel J. Coster**, San Francisco, CA (US); **Daniele De Iuliis**, San Francisco, CA (US); **Evans Hankey**, San Francisco, CA (US); **Richard P. Howarth**, San Francisco, CA (US); **Jonathan P. Ive**, San Francisco, CA (US); **Steve Jobs**, Palo Alto, CA (US); **Duncan Robert Kerr**, San Francisco, CA (US); **Nicholas George LeBreton**, San Francisco, CA (US); **Pinida Jan Moonlsintong**, San Francisco, CA (US); **Scott A. Myers**, San Francisco, CA (US); **Shin Nishibori**, Portola Valley, CA (US); **Matthew Dean Rohrbach**, San Francisco, CA (US); **Peter Russell-Clarke**, San Francisco, CA (US); **Christopher J. Stringer**, Woodside, CA (US); **Tang Yew Tan**, San Francisco, CA (US); **Eugene Antony Whang**, San Francisco, CA (US); **Michael Benjamin Wittenberg**, Sunnyvale, CA (US); **Rico Zorkendorfer**, San Francisco, CA (US)
(73) Assignee: **Apple Inc.**, Cupertino, CA (US)
(*) Notice: This patent is subject to a terminal disclaimer.
(**) Term: **14 Years**
(21) Appl. No.: **29/384,915**
(22) Filed: **Feb. 4, 2011**
(51) **LOC (9) Cl.** **14-04**
(52) **U.S. Cl.** **D14/439**
(58) **Field of Classification Search** ..... D14/341-347, D14/424, 425, 432-453, 464, 468, 469, 471, D14/438, 496, 511, 138 AA, 138 AD, 138 C, D14/138 G, 203.1-203.8, 217, 238.1, 248, D14/250, 257, 299; 361/679.01, 679.02, 361/679.03, 679.3, 679.55, 679.56; 455/550.1, 455/556.1, 556.2, 575.1, 575.3-575.5, 575.8, 455/90.3

(57) **CLAIM**

The ornamental design for a backplate of an electronic device, as shown and described.

DESCRIPTION

FIG. 1 is a bottom front perspective view of a backplate of an electronic device showing our new design;
FIG. 2 is a bottom rear perspective view thereof;
FIG. 3 is a front view thereof;
FIG. 4 is a rear view thereof;
FIG. 5 is a top view thereof;
FIG. 6 is a bottom view thereof;
FIG. 7 is a right side view thereof; and,
FIG. 8 is a left side view thereof.
